CLAIM

The ornamental design for an overlapping roller blind system,
as shown and described.

DESCRIPTION

FIG. 1 is a perspective view of an overlapping roller blind
system.FIG. 2 is a front elevation view of the overlapping roller blind
system.FIG. 3 is a rear elevation view of the overlapping roller blind
system.FIG. 4 is a left side elevation view of the overlapping roller
blind system.FIG. 5 is a right side elevation view of the overlapping roller
blind system.FIG. 6 is a top plan view of the overlapping roller blind
system; and,FIG. 7 is a bottom plan view of the overlapping roller blind
system.The broken lines immediately adjacent the areas with surface
shading represent the bounds of the claims and all other
broken lines represent portions of the design that form no part
of the claim. None of the broken lines form a part of the
claimed design.
